CLAIM

The ornamental design for a smartphone, as shown and described.

DESCRIPTION

FIG. 1 is a perspective view of the invention from the front left side.

FIG. 2 is a perspective view from the rear right side thereof.

FIG. 3 is a front elevation view thereof.

FIG. 4 is a rear elevation view thereof.

FIG. 5 is a left elevation view thereof.

FIG. 6 is a right elevation view thereof.

FIG. 7 is a top elevation view thereof; and,

FIG. 8 is a bottom elevation view thereof.

The broken lines shown in the figures that are immediately adjacent to the shaded areas and define unshaded regions represent the bounds of the claim. All other broken lines, including the features within broken line boundaries and the broken lines beneath the front glass at the top and bottom of the display, are directed to environment. The broken lines form no part of the claimed design.

1 Claim, 8 Drawing Sheets
